[57] CLAIM

The ornamental design for spring loaded clip for a hair roller or the like, substantially as shown and described.

DESCRIPTION

FIG. 1 is a side elevational view of the spring loaded clip for a hair roller or the like showing my new design; FIG. 2 is a right end elevational view thereof, the left end elevational view being identical thereto;

FIG. 3 is a top plan view thereof;

FIG. 4 is a right end elevational view showing the limit of opening thereof;

FIG. 5 is a bottom plan view of FIG. 4; and

FIG. 6 is a right end elevational view showing the limit of closure thereof.

FIG.1

FIG. 2

FIG. 3

FIG. 4

FIG. 6

FIG. 5
